DESIGN FOR A DOOR CLOSER

Glen Holland, Bronxville, N. Y., and Robert S.
Potter, Old Greenwich, Conn.

Application April 25, 1941, Serial No. 100,616

Term of patent 14 years

To all whom it may concern:

Be it known that we, Glen Holland and Robert S. Potter, citizens of the United States, residing, respectively, at Bronxville, in the county of Westchester and State of New York, and at Old Greenwich, in the county of Fairfield and State of Connecticut, have invented a new, original, and ornamental Design for a Door Closer, of which the following is a specification, reference being had to the accompanying drawing, forming part thereof.

Fig. 1 is an elevational view of a door closer, showing our new design; and Fig. 2 is a top plan view thereof.

We claim:

The ornamental design for a door closer, as shown.

GLEN HOLLAND.
ROBERT S. POTTER.
